UNITED STATES PATENT OFFICE.

BROR F. STENMAN, OF WORCESTER, MASSACHUSETTS, ASSIGNOR TO J. HENRY LINDBERG, OF WORCESTER, MASSACHUSETTS.

ELECTRIC VALVE-GRINDER.

1,294,318.

Specification of Letters Patent. Patented Feb. 11, 1919.

Application filed May 24, 1918. Serial No. 236,402.

To all whom it may concern:

Be it known that I, BROR F. STENMAN, a citizen of the United States, residing at Worcester, in the county of Worcester and 5 State of Massachusetts, have invented new and useful Improvements in Electric Valve-Grinders, of which the following is a specification.

This invention relates to an electric valve 10 grinder, and the object is to provide certain novel means for imparting an oscillating movement to the shaft carrying the bit, whereby an additional movement is secured during the travel, through a given angle, of 15 the crank arm actuating the shaft.

A further object is to provide for imparting to the crank arm an additional or supplemental movement just before the arm reaches the limit of its travel in a given 20 direction, thereby increasing the period of frictional contact during the travel of the arm through a given angle.

A still further object is to provide certain 25 novel means for connecting the lead wires with the motor actuating the main shaft, and certain novel means for controlling the switch.

A still further object is to provide for 30 the employment of different forms of bits for engaging the valve, certain of the bits including a universal joint.

With the foregoing and other objects in view, the invention consists in the novel construction, combination, and arrangement of 35 elements hereinafter described and claimed.

In the accompanying drawings:

Figure 1 is a view in vertical section, parts being shown in elevation.

Fig. 2 is a top plan view.

Fig. 3 is a section on the line 3—3 of 40 Fig. 1.

Figs. 4 and 5 are details showing different positions of the crank arm and pin co-operating therewith.

Figs. 6 to 9 are details showing different 45 forms of bits.

Fig. 10 is a bottom plan view of Fig. 9.

Fig. 11 is a section through the handle, showing certain elements of the switch.

Fig. 12 shows one of the operating pins 50 detached from the slidable member of the switch.

A casing includes an upper casing member 10 and a lower casing member 12 carrying a tubular extension 14, said member 12

being secured in position by means of screws such as 15 entering the plate member 16 located between the two casing members. Plate member 16 is retained in position by means of rods 17 threaded at their ends and 60 engaged by nuts at the opposite ends thereof.

The motor 20 is shown more or less conventionally, and the armature shaft 21 carries a pinion 22 meshing with a gear wheel 23 having a pinion 24 rigid therewith. 65

This pinion 24 meshes with the gear wheel 25 mounted on a short shaft 26. Gear wheel 25 carries a pin 27 engaging and operating a slotted arm 30. The slot 31 of the arm is of the form shown and serves a particular 70 purpose as specified below. Arm 30 is rigid with reference to shaft 32 passing through the tubular member 14, and imparts to the shaft an oscillating movement.

A sleeve 33 is keyed to shaft 32 in any 75 suitable manner such as by passing the pin 34 through the sleeve and shaft. A loose washer 35 is located between the sleeve and the end of member 14.

Sleeve 33 is slotted transversely as shown 80 at 38, and within this slot is mounted a bit, the latter being secured by means of a pin 39. The bit shown in Fig. 1 is designated 40 and is designed to engage an engine valve of the type having two spaced apertures formed therein. This bit is also shown in Fig. 7, and in Fig. 8 I have shown a bit 41 having an edge 42 for engaging that form of valve having a slot extending transversely thereof, for the purpose well understood. 90

In Fig. 9 I have shown a bit of disk form, and designated 43, the lower side being shown in plan in Fig. 10 as being provided with pins 44. This bit is secured to the 95 sleeve 33 by means of a yoke 45 pivotally connected at 46 with an element 47 which in turn is connected by pivot 48, extending at another angle, with ears 49 carried by disk 43. This construction provides a substantially universal movement between the shaft 32 and the valve engaged by disk 43 and the pins thereon.

Referring to Figs. 4 and 5, special attention is directed to the formation of the slot 100 31, the purpose being to provide for an additional or supplemental movement of the valve within the extreme limit of movement thereof, thus increasing the effective frictional contact during each complete 110.

movement of the arm 30. Just before arm 30 reaches the limit of its movement in either direction, it is moved backwardly to a slight extent with reference to the main movement of the arm at this particular instant, the arm then again moving forwardly to the limit of its travel in that direction, at which time the direction of the movement is reversed.

10 The handle is designated 50 and includes bore 51 through which the wires extend. These lead wires are inclosed in a single insulating covering 52 and a collar or the like 53 is secured at about the point shown, in order that it may abut the threaded and flanged sleeve 54, thereby preventing strain on the connections between the lead wires and the terminals, the latter not being shown.

15 In Figs. 11 and 12 I have shown certain details of the switch which may be employed. This switch is mounted in the deflected tubular portion 55 of the handle and is under the control of detachable pins 56 and 57, the pins being removable in order to prevent the manipulation of the switch by individuals not authorized to use the implement. Each pin carries a plurality of springs 58 engaging a cut-away portion 59 of the slideable member 60. This slideable member has pivotally connected therewith a pin 61 passing loosely through the central portion of a yoke 63, a spring 64 being interposed as shown for a purpose readily ap-

parent. Yoke 63 is pivotally mounted in 35 ears 64, and the slide 60 is movable transversely of the yoke by the operation of either pin 56 or 57. This movement of the slide 60 throws the yoke into engagement with upwardly extending spring elements 66 so located as to be engaged by the central portion of the yoke, for the purpose of completing an electric circuit including the motor 20.

40 What is claimed is:

1. In a device of the class described, a 45 casing, a motor mounted therein, a shaft to be driven by the motor, a bit carried by the shaft, an arm mounted on the shaft for imparting an oscillating movement thereto, a gear wheel, means for driving the latter 50 from the motor, and a pin carried by the gear wheel, said arm being slotted, and the slot thereof being of uniform width and extending in two directions with reference to the main axis of the arm. 55

2. In a device of the class described, a casing, a motor mounted therein, a shaft, a bit carried by the shaft, an arm for imparting an oscillating movement to the shaft and the bit, said arm being slotted lengthwise 60 and including an angular portion, a wheel driven from the motor, a pin carried by the wheel and extending into the slot, said slot being proportioned to impart an additional oscillating movement to the arm, within the 55 limits of the principal movement thereof.

In testimony whereof I affix my signature.
BROR F. STENMAN.
